US0D1093873S

(12) **United States Design Patent** (10) Patent No.: **US D1,093,873 S**
(45) Date of Patent: ** Sep. 23, 2025

(54) HEAD SUPPORT FOR A CHILD CARRIER	6,179,187 B1	1/2001	Lemire et al.
(71) Applicant: Lalabu LLC , Statham, GA (US)	6,240,564 B1	6/2001	Te Kanawa
(72) Inventors: Brian Fosse , Bend, OR (US); Mirona Motoc , Seattle, WA (US)	6,409,060 B2	6/2002	Donine
(73) Assignee: Lalabu LLC , Stillwater, MN (US)	6,460,746 B1	10/2002	Amram
(**) Term: 15 Years	6,598,771 B2	7/2003	Norman
(21) Appl. No.: 29/860,709	6,666,361 B1	12/2003	Lin
(22) Filed: Nov. 22, 2022	6,776,317 B1	8/2004	Parker

CLAIM

The ornamental design for a head support for a child carrier as shown and described.

DESCRIPTION

FIG. 1 is a front perspective view of a first embodiment of a head support for a child carrier showing the claimed design;

FIG. 2 is a front elevation view of the first embodiment; FIG. 3 is a rear elevation view of the first embodiment; FIG. 4 is a left side elevation view of the first embodiment; FIG. 5 is a right side elevation view of the first embodiment; FIG. 6 is a top plan view of the first embodiment; and FIG. 7 is a bottom plan view of the first embodiment.

FIG. 8 is a front perspective view of a second embodiment of a head support for a child carrier showing the claimed design; in this view it can be seen that the top seam of the

head support is cut to have a curved shape when the head support is in an extended position;

FIG. 9 is a front elevation view of the second embodiment; FIG. 10 is a rear elevation view of the second embodiment; FIG. 11 is a left side elevation view of the second embodiment;

FIG. 12 is a right side elevation view from the left side of the second embodiment;

FIG. 13 is a top plan view of the second embodiment; and

FIG. 14 is a bottom plan view of the second embodiment.

FIG. 15 is a rear perspective view of a third embodiment of a head support for a child carrier showing the claimed design;

FIG. 16 is a front elevation view of the third embodiment;

FIG. 17 is a rear elevation view of the third embodiment;

FIG. 18 is a left side elevation view of the third embodiment; FIG. 19 is a right side elevation view from the left side of the third embodiment;

FIG. 20 is a top plan view of the third embodiment; and

FIG. 21 is a bottom plan view of the third embodiment.

FIG. 22 is a rear perspective view of a fourth embodiment of a head support for a child carrier showing the claimed design;

FIG. 23 is a front elevation view of the fourth embodiment;

FIG. 24 is a rear elevation view of the fourth embodiment;

FIG. 25 is a left side elevation view of the fourth embodiment;

FIG. 26 is a right side elevation view from the left side of the fourth embodiment;

FIG. 27 is a top plan view of the fourth embodiment; and,

FIG. 28 is a bottom plan view of the fourth embodiment.

The dash broken lines represent stitching on the head support for child carrier and form no part of the claimed design. The dash-dot-dash broken lines show environment and form no part of the claimed design.
